UNITED STATES PATENT OFFICE.

CHARLES F. MORGAN, OF TAYLOR, MINNESOTA.

BUNDLE-CARRIER FOR SELF-BINDING HARVESTERS.

SPECIFICATION forming part of Letters Patent No. 349,895, dated September 28, 1886.

Application filed December 16, 1885. Serial No. 185,841. (No model.)

To all whom it may concern:

Be it known that I, CHARLES F. MORGAN, of Taylor, in the county of Traverse and State of Minnesota, have invented a new and useful 5 Improvement in Bundle-Carriers for Self-Binding Harvesters, of which the following is a full, clear, and exact description.

Reference is to be had to the accompanying drawings, forming a part of this specification, 10 in which similar letters of reference indicate corresponding parts in all the figures.

Figure 1 is a plan view of my improvement shown as applied to the frame of a harvester, parts of the harvester-frame being shown in 15 section and parts being broken away. Fig. 2 is a front elevation of the same, partly in section through the lines *x x x x*, Fig. 1, and parts being broken away. Fig. 3 is a sectional side elevation of the same, part being broken away. 20 Fig. 4 is a rear elevation of the catch-bar, catch-spring, and latch, and showing parts of the catch-bar support and bundle-platform.

The object of this invention is to provide 25 bundle-carriers for self-binding harvesters simple in construction, easily operated, and reliable in operation.

The invention consists in the construction and combination of various parts of the bundle-carrier, as will be hereinafter fully described.

30 A represents the frame of a harvester. To the side bar of the frame A are attached brackets B, to which are secured, by a key or other suitable means, the ends of the rod C. The rod C passes through eyes at the ends of the 35 inner edge of the metal plate D, to which is bolted the inner end of the bar E. The bar E is supported in a horizontal position by the U-shaped strap F, to the bend of which the said bar E is bolted. The ends of the strap F 40 are secured to the binder-frame L. By this construction the supporting-bar E and the platform G can be readily adjusted forward or back to correspond with the adjustment of the binder.

45 G is the platform that receives the bundles, and which is hinged near its forward end to the bar E. The platform G is provided with narrow upwardly-projecting boards at its outer side and forward end, to keep the bundles in 50 place upon it. To the forwardly-projecting end of the inner base-bar of the platform G is

attached a box, H, to receive gravel or other heavy material to give the said weight-box sufficient gravity to raise the platform G into a horizontal position after being tilted by the 55 weight of the bundles. The rear end, I, of the inner base-bar of the platform G projects to serve as a latch to engage with the catch-bar J, by which the said platform is supported in a horizontal position while receiving and carrying the bundles.

The inner side of the lower end of the catch-bar J is beveled, so that the latch I will engage with it automatically when the platform G is raised into a horizontal position. In the inner 65 edge of the catch bar J, just above the bevel at its lower end, is formed a recess to receive the latch I and support the platform G in a horizontal position.

The catch-bar J, at a point a little above its 70 center, is pivoted to the forked outer end of a bar, K, which rests upon a bar of the binder-frame L, and is secured at its inner end to the lower side of another bar of the said binder-frame, so as to firmly support the catch-bar J. 75

The upper end of the catch-bar J is pressed outward to cause its lower end to engage automatically with the latch I and hold it in gear with the said latch by a spring, M, attached to the fulcrum-bar K, with its free end resting 80 against the inner side of the upper end of the said catch-bar J. To the upper end of the catch-bar J is attached the end of a trip-cord, N, which passes over a pulley, O, pivoted to a support attached to the top of the frame A, 85 around a pulley, P, pivoted to a support attached to the bar Q, that supports the seat R, and its other end is attached to an arm of the bent foot-lever S, journaled to a bearing, T, attached to the said seat-bar Q, in such a position that it can be conveniently reached and operated by the driver with his foot. With this construction, when the desired number of bundles have been received upon the platform G, the driver operates the foot-lever S, which 90 withdraws the catch-bar J from the latch I and allows the weight of the bundles to tilt the platform G, when the said bundles slide off the said platform to the ground. As the bundles fall to the ground the gravity of the weight-box 100 H causes the platform G to return to a horizontal position, when the catch-bar J engages with

the latch I and supports the said platform in position to again receive bundles. With this construction, also, the bundle-carrier, when not required for use, or when the harvester is to be drawn through a barway or other narrow passage, can be readily detached by removing the rod C and taking out the bolt that secures the bar E to the supporting-strap F.

Having thus fully described my invention, I claim as new and desire to secure by Letters Patent—

1. The combination, with a harvester-frame, A, of the supporting-bar E, secured to the said frame, the platform G, hinged near one end to the said bar, and provided at its hinged end with a weight-box, H, and at its other end with a latch, I, the pivoted catch-bar J, provided with a spring, M, and the cord N, the guide-pulleys O P, and bent foot lever S, substantially as herein shown and described, whereby

the said platform will be securely supported, can be readily tripped, and will return automatically to its normal position, as set forth.

2. The combination, with the harvester-frame A, provided with the brackets B and 25 the rod C, of the hinged platform G, the bar E, to which the platform is hinged, the eye-plate D, secured to the said bar and fitted to turn and slide back and forth upon the said rod, and the U-shaped strap F, secured to the 30 said bar and the binder-frame, substantially as herein shown and described, whereby provision is made for adjusting the platform forward or backward to correspond with the adjustment of the binder.

CHAS. F. MORGAN.
